(57) **CLAIM**

I claim the ornamental design for a network computing terminal, as shown and described.

DESCRIPTION

FIG. 1 is a perspective view of a network computing terminal showing my new design;

FIG. 2 is a front elevation view of the network computing terminal;

FIG. 3 is a rear elevation view of the network computing terminal. The broken lines showing the ports in FIG. 3 are for the purpose of illustrating unclaimed portions and form no part of the claimed design;

FIG. 4 is a left side elevation view of the network computing terminal;

FIG. 5 is a right side elevation view of the network computing terminal. The broken lines showing the ports in FIG. 5 are for the purpose of illustrating unclaimed portions and form no part of the claimed design;

FIG. 6 is a top plan view of the network computing terminal; and,

FIG. 7 is a bottom plan view of the network computing terminal. The broken lines showing various portions of FIG. 7 are for the purpose of illustrating unclaimed portions and form no part of the claimed design.
